UNITED STATES PATENT OFFICE.

FRANK S. SMITH, OF LOS ANGELES, CALIFORNIA.

DESIGN FOR A GOLF-CLUB HEAD.

Application filed August 6, 1927. Serial No. 23,014. Term of patent 14 years.

To all whom it may concern:

Be it known that I, FRANK S. SMITH, a citizen of the United States, residing at Los Angeles, in the county of Los Angeles and State of California, have invented a new, original, and ornamental Design for Golf-Club Heads, of which the following is a specification, reference being had to the accompanying drawing, forming part thereof.

Fig. 2 is a side elevation;

Fig. 3 is a front end view; and

Fig. 4 is a top plan view.

I claim:

The ornamental design for a golf club head substantially as shown.

FRANK S. SMITH.
